UNITED STATES PATENT OFFICE

JACOB J. KAGAN, OF LOS ANGELES, CALIFORNIA

DESIGN FOR A RING

Application filed February 2, 1931. Serial No. 38,518. Term of patent 14 years.

To all whom it may concern:

Be it known that I, JACOB J. KAGAN, a citizen of the United States, residing at Los Angeles, in the county of Los Angeles and State of California, have invented a new original, and ornamental Design for a Ring, of which the following is a specification, reference being had to the accompanying drawing, forming part thereof.

I claim:
The ornamental design for a ring, as shown.
In testimony whereof, I hereunto set my hand.

JACOB J. KAGAN.
